UNITED STATES PATENT OFFICE.

MINOSAKU TAKAHASHI, OF HARLOWTON, MONTANA.

VESSEL-CLOSURE.

1,014,536.

Specification of Letters Patent.

Patented Jan. 9, 1912.

Application filed May 24, 1910. Serial No. 563,122.

To all whom it may concern:

Be it known that I, MINOSAKU TAKAHASHI, a subject of the Emperor of Japan, residing at Harlowton, in the county of Meagher, 5 State of Montana, have invented certain new and useful Improvements in Vessel-Closures; and I do hereby declare the following to be a full, clear, and exact description of the invention, such as will enable 10 others skilled in the art to which it appertains to make and use the same.

The invention relates to a receptacle closure and more particularly to the class of closures for bottles, jars or the like.

15 The primary object of the invention is the provision of a closure in which the mouth portion of a receptacle may be tightly closed so as to prevent leakage of the contents of the receptacle should it become 20 upset or accidentally overturned.

Another object of the invention is the provision of a closure of this character in which the sealing cap thereof can be readily detached at will so that it may be replaced 25 when required and which cap will serve to tightly close the mouth of the receptacle to prevent leakage of its contents should the receptacle become overturned.

A further object of the invention is the 30 provision of a closure which is capable of being mounted upon bottle necks or the body of other receptacles of varying sizes and which closure may be readily removed at will so that it may be cleaned to maintain 35 the same sanitary.

A still further object of the invention is to provide a closure of the character described possessing advantages in points of simplicity 40 security and convenience.

With these and other objects in view the invention consists in the construction, combination and arrangement of parts as will be hereinafter more fully described, illustrated in the accompanying drawings disclosing 45 the preferred form of embodiment of the invention and pointed out in the claim hereunto appended.

In the drawings:—Figure 1 is a side elevation of a bottle with the invention applied thereto. Fig. 2 is a top plan view thereof. Fig. 3 is a vertical longitudinal sectional view. Fig. 4 is a detailed perspective view of the securing member for embracing the bottle neck. Fig. 5 is a detailed perspective 55 view of the bail member for supporting the closure cap.

Similar reference characters indicate corresponding parts throughout the several views in the drawings.

Referring to the drawings by numerals, 60 6 designates a bottle having at its mouth portion an outer peripheral flange 7, the bottle being of the ordinary well-known form. Fitted over the mouth portion of the bottle 6 is a cap 8 the same being in the 65 form of an inverted cup shaped body adapted to receive a portion of the flange 7 when the said cap is tightly fitted upon the bottle.

Secured transversely on the outer face of 70 the cap 8 are a series of strap loops forming alining eyes 9 in which is detachably engaged a bail member 10 the same being bent near one end to form a spring coil or convolution 11 and adjacent this coil the said 75 bail member 10 is further bent to form an eye terminal 12 the same engaging a central bight 13 formed in a split ring member 14 the latter being preferably formed from a single strand of wire bent to embrace the 80 neck portion of the bottle 6 for the mouth of the bail member 10 thereon, one end of the ring member 14 being bent to form a hook terminal 15 and the other end being bent to from a vertical shank 16 rising a 85 slight distance above the plane of the ring member 14 and terminates in an outwardly bent hook bill 17 the latter adapted to engage with the free end of the bail member 10 and securing the cap upon the bottle. 90 The hook terminal 15 is adapted to engage the shank 16 to detachably secure the ring member 14 about the bottle neck.

It will be apparent that when the bail member 10 is engaged with the hook bill 17 95 on the ring member 14 embracing the bottle 6 the coil 11 will exert an upward tension on the bail member 10 thus maintaining it in locked engagement with the hook bill 17 so as to obviate possibility of accidental disengagement of the bail from the said bill 17. Furthermore due to the disposition of the coil 11 and the hook bill 17 the cap will be held so as to prevent the discharge or leakage of the contents of the bottle. 100

105 What is claimed is:

The combination with a vessel of a plurality of strands of wire, one of said strands being bent to surround the neck of the vessel in the form of a ring, an eye formed at one 110 side of the ring, a vertical shank formed at the opposite side of the ring by bending one

terminal of the strand laterally with respect to the ring, a hook formed upon said shank, the other of said strands being bent to produce a bail bisecting the mouth of the receptacle to engage the hook formed upon the shank, an arm formed at one end of the bail, a hook formed at the terminal of said arm to engage the eye provided upon the ring, a closure attached to said bail, and

convolutions produced by bending the strand 10 comprising the arm substantially as and for the purposes set forth.

In testimony whereof, I affix my signature, in presence of two witnesses.

MINOSAKU TAKAHASHI.

Witnesses:

W. C. HUSBAND,
R. A. GOOD.
